UNITED STATES PATENT OFFICE.

ANDREW STARK, OF CHICAGO, ILLINOIS.

RAIL-SECURING DEVICE.

1,095,432.

Specification of Letters Patent.

Patented May 5, 1914.

Application filed June 28, 1913. Serial No. 776,209.

To all whom it may concern:

Be it known that I, ANDREW STARK, a citizen of the United States, residing at Chicago, in the county of Cook and State of Illinois, have invented new and useful Improvements in Rail-Securing Devices, of which the following is a specification, reference being had to the accompanying drawings, forming a part thereof.

10 The purpose of this invention is to provide a cheap and dependable fastening device for securing railway rails to ties, and preferably the device is so made as to be adaptable for use either with wooden ties or 15 with molded concrete ties.

It consists of the features and elements described and shown in the drawings as indicated by the claims.

In the drawings: Figure 1 is a sectional view of a wooden tie and a rail showing the preferred form of the securing device in position. Fig. 2 is a front face view of the "spike member" of the securing device. Fig. 3 is a rear face view of said spike member. Fig. 4 is a section taken as indicated at line 4—4 on Fig. 1. Fig. 5 is a view similar to Fig. 1 showing a modified form of spike member in position. Fig. 6 is a sectional view of a concrete tie with a rail lodged thereon showing the application of the preferred form of securing device to this type of construction. Fig. 7 illustrates a modified form of securing device for use in concrete ties. Fig. 8 illustrates a further modification of the device for use in concrete ties. Fig. 9 is a transverse section taken as indicated at line 9—9 on Fig. 7. Fig. 10 is a sectional view similar to Fig. 1 showing the rail supported on a shim block, 40 F, and showing the fastening device replaced for securing the rail in this position. Fig. 11 is a top plan view of a rail partly in section showing the application of the fastening in a way to prevent rail creeping. Fig. 12 is a detail section at line 12—12 on Fig. 11. Fig. 13 is a detail section at line 13—13 on Fig. 11.

The fastening device which is the subject of this invention comprises essentially two members which will be referred to as the "spike member" and the "wedge key," respectively, and which are so formed and positioned relatively to each other as to compose a fastening capable of more effectively resisting forces tending to draw it from the tie than is the ordinary railway spike, and

also having other advantages over existing fastenings as will presently appear. In the preferred form illustrated in Fig. 1, the spike member, A, is provided with a head, A¹, similar in form to the head of a standard spike except that it has no projection at the rear face, *i. e.* at the side opposite the rail, C. Just below the head, A¹, the cross section of the spike member is substantially square and for its full length the front face which is toward the rail, C, is of uniform width. As clearly shown in the drawing, however, the body of the spike is tapered divergently from the head downward, and as indicated in Fig. 3 this widening is at the expense of the thickness which narrows downwardly to a minimum value at the heel, A². From this heel the spike is sharpened to a chisel point at A³, so that it may be driven into the wooden tie, D, in the usual manner, and by virtue of the proportions thus obtained the spike is so "balanced" that it may be driven straight and true without difficulty.

On account of the excess width of the spike member at its heel, A², it will be evident that after such a spike has been driven into the tie there will be a hole in the wood just back of the spike at the top surface of the tie. The wedge key, B, is now inserted into this hole and driven down to a position in which its overhanging head is far enough above the tie surface to be readily engaged by a claw if it should be desired to remove the fastening; but at this position, the thickness of the wedge key is sufficient to completely fill the hole made by the spike member, A, thus effectively preventing the entrance of water, and also by its wedging action materially increasing the frictional grip of the spike member on the wood of the tie. Furthermore, it will be seen that since under most conditions slippage between the opposing surfaces of the wedge key and the spike member will occur more easily than between either of said members and the wood, any lifting tendency of the rail flange, C¹, operating to draw the spike member, A, from the tie will cause it to slip against the wedge key; but the slightest relative movement in this direction will only increase the effective width of the two members of the fastening and thus increase the frictional hold of the spike member upon the tie, rendering it practically impossible to release the fastening by drawing upward upon the

spike member unless sufficient force is employed to actually rend the tie itself.

While in the direction transverse to the rail the key member, B, is of varying thickness so as to constitute a wedge, it will be understood from Fig. 4 that the width of this member in the transverse direction (that is, in the direction of extent of the track) is practically uniform, and may be equal to or greater than the uniform width of the front face of the spike member, A. In this way, the wedge key furnishes a greater bearing area for the securing device against the material of the tie than is afforded by the tapering rear face of the spike member itself; and by properly proportioning these elements to the crushing strength of the tie, it is evident that a fastening may be provided which will have to actually bend in order to permit lateral movement of the rail, C. By virtue of the two-part construction of this fastening device, the withdrawal of the wedge key, B, permits the removal of the entire fastening without injury to the tie, and if desired may be replaced in the same hole of the tie without any sacrifice of security, since its tightness in the tie depends merely upon the extent to which the wedge key, B, is driven down. Thus a worn rail may be quickly removed and replaced by a new rail without changing the ties or without driving new spikes into new holes. Fig. 5 suggests a modification of the spike member which would permit the replacement of one size of rail by a different size without forming new holes in the ties to receive the fastening devices. It consists in providing a slightly longer overhanging head portion, A⁴, than the head, A¹, shown in Fig. 1, but limiting the engagement of such head with the rail flange, C, by forming a stop shoulder, A⁵, on the under side of such head. If then the track were originally laid with comparatively light rails secured by the form of spike shown in Fig. 5, these rails could later be replaced with heavier ones and secured by the form of fastening shown in Fig. 1 set into the same hole as was originally occupied by the type of Fig. 5.

Figs. 6 to 9 illustrate the application of the invention to molded concrete ties, Fig. 6 indicating that it is only necessary to mold the concrete tie, E, with a mortise, E¹, in which the same form of fastening may be employed as is shown for use in wooden ties. However, since for this use the sharpened point of the spike member, A, is not essential, and since nothing is gained by the thinning of the rear face of said member, it is deemed preferable to employ a specially formed spike member, A¹⁰. This member may be cast or forged with front and rear faces both of uniform width, and for the sake of economy of material its cross section

may be reduced to form a web at, A¹¹. (See Fig. 9.) The key member, B, is practically identical with the keys shown in the preceding figures. Fig. 7 illustrates a form of "spike member" corresponding to the pointed form shown in Fig. 5, having the shoulder, A⁵, positioned on the under side of the overhanging head, A⁴, and Fig. 8 illustrates the form corresponding to the pointed spike shown in Fig. 1, and further indicates an additional use of this shape of fastening, viz., for accommodating the fish plate, C², at the rail joint. Preferably, all concrete ties which are designed to receive these fastenings will be cast with a notch, E², at the upper end of the mortise, E¹, so as to permit the shoulder, A⁵, to extend somewhat below the top surface of the rail to more certainly prevent the rail flange, C¹, from working laterally under this shoulder and causing even a slight spreading of the rails. Although this notch, E², will have no function when the form of hook or spike member shown in Fig. 8 is employed, its presence will not affect the stability of the rail since the latter does not rest directly on the concrete but upon cushion blocks, E³, lodged in the tie, E.

Under normal conditions, as already explained, any lifting force tending to draw the spike member from the tie, if it did produce any movement of this member of the fastening, would necessarily cause slippage between said member and the wedge key, thus increasing the effective width of the fastening and checking further movement. It is deemed preferable, however, in forming the mortise, E¹, in the concrete tie to make its opposing walls, E⁴ and E⁵, taper divergently downward, so that if for any reason the frictional engagement of the spike member and wedge key with each other should prove stronger than the friction of said members against the material of the tie, it would still be impossible for any lifting force to materially loosen the fastening. Similarly in the case of wooden ties the members, A and B, may be so proportioned that when secured in position, as indicated in Fig. 1, their aggregate width is greater near the lower end than at the upper end; but, this construction need in no way interfere with the intentional removal of the fastening by first withdrawing the wedge key, B.

As is well known, it is frequently necessary to shim up a rail for re-leveling the track, and where wooden ties are used the rail gradually sinks into the wood of the ties leaving the spike heads out of contact with the rail flange, and it becomes necessary to tap the spikes down to render the rails secure. My fastening device permits all such adjustments to be made without difficulty by reason of the fact that the face of the spike

member which engages the tie is entirely plain, that is, without serrations or projections such as would positively engage the material of the tie as distinguished from the purely frictional engagement which is obtained with this plain surface. The compressive action of the wedge key, B, may at any time be momentarily overcome by a quick tap upon the head of the spike member, A, and the wedge key can be simultaneously withdrawn with any convenient tool. This permits the complete removal of the fastening or its readjustment to any desired position, with no sacrifice of efficiency as a rail fastening in such new position.

If desired, the spike member having the shoulder, A⁵, may be employed to prevent rail creeping by notching either the rail flange at C³, or the fish plate at C⁴, at the rail joint to accommodate this shoulder, A⁵, as indicated in Figs. 11, 12 and 13. In most situations, the notching of the fish plates at the joints would be sufficient, and with this arrangement it will be seen that only one form of spike member would be needed for a given installation, the shoulders, A⁵, of the spike members serving to position the rails laterally, as previously explained, and said shoulders being accommodated in the notches, C⁴, in the fish plates at each rail joint, thus obviating the use of the special form of spike member shown in Fig. 8.

I claim:—

1. A rail fastening, comprising a spike member having a head for engaging the rail flange and a body portion widening downwardly from said head, the lower end of said body portion being sharpened to adapt said spike member to be driven into a tie, and means for retaining said spike member in the tie.

2. A rail fastening comprising a spike member having a head for engaging the rail flange and a body portion widening downwardly from said head, one face of said body portion being plain and the lower end of said body being beveled back from said face to form a chisel point, and a wedge key of opposite taper adapted for insertion in the tie against the opposite face of said spike body for maintaining frictional engagement of said plain face with the tie.

3. A rail fastening comprising a spike member having a head for engaging the rail flange and a body portion widening downwardly from said head, one face of said body portion being plain and of uniform width throughout its length, the lower end of said body being beveled back from said face to a heel to form a chisel point, said body tapering in thickness from said plain face to a minimum value at said heel, and a wedge key narrowing downwardly and adapted for insertion in the tie against the opposite face of said spike body for main-

taining frictional engagement of its said plain face with the tie.

4. A rail fastening comprising a spike member having a head for engaging the rail flange and a body portion widening downwardly from said head, the front face of said body portion toward the rail being plain and of uniform width throughout its length, the lower end of said body being beveled back from said face to a heel to form a chisel point, said body tapering in thickness from said plain face to a minimum value at said heel, and a wedge key narrowing downwardly and adapted for insertion in the tie against the rear face of said spike body for maintaining frictional engagement of its said plain face with the tie.

5. In combination with a railway tie and a rail lodged thereon, said tie being formed with a mortise substantially perpendicular to its rail-supporting surface, the opposing walls of said mortise being approximately parallel, a rail fastening composed of a spike member having a head for engaging the rail flange and a body portion widening downwardly from said head, one face of said body portion being plain and adapted for frictional engagement with one of said opposing walls of the mortise, and a wedge key of opposite taper adapted for insertion in said mortise against the opposite face of said spike body for maintaining such frictional engagement of its plain face with the tie.

6. In combination with a railway tie and a rail lodged thereon, said tie having a vertical mortise formed with a pair of opposing walls slightly divergent downward, a rail fastening composed of a spike member having a head for engaging the rail flange, and a body portion widening downwardly from said head, one face of said body portion being plain and adapted for frictional engagement with one of the said diverging walls of the mortise, and a wedge key of opposite taper adapted for insertion in said mortise against the opposite face of said spike body for maintaining such frictional engagement of its plain face with the tie.

7. A rail fastening, comprising a member having a head for engaging the rail flange and a body portion adapted for insertion in a tie, and means for securing said body portion in the tie; said member having a shoulder formed on the under side of its head for engaging the rail flange to correctly position the rail on the tie.

8. A rail fastening composed of a spike member having a head for engaging the rail flange and a body portion widening downwardly from said head, and a wedge key of opposite taper adapted for insertion in the tie against said spike member, said member having a shoulder formed on the

under side of its head for engaging the rail flange to correctly position the rail on the tie.

9. In combination with a railway tie and a rail lodged thereon, said tie having a vertical mortise formed with a pair of opposing walls approximately parallel, a rail fastening comprising a spike member having a head for engaging the rail flange, and a body portion widening downwardly from said head, and a wedge key of opposite taper adapted for insertion in the tie against the spike member, said member having a shoulder formed on the under side of its head for engaging the rail flange to correctly position the rail on the tie, and said tie having a notch in its upper surface positioned and dimensioned to accommodate the lower portion of said shoulder.

10. In combination with a railway tie and a rail lodged thereon, said tie having a vertical mortise formed with a pair of opposing walls approximately parallel, a rail fastening comprising a spike member having a head for engaging the rail flange and a body portion widening downwardly from said head, and a wedge key of opposite taper adapted for insertion in the tie against the spike member, one face of said spike body being plain and adapted for frictional engagement with one of said opposing walls of the mortise, said spike member having a shoulder formed on the under side of its head, the rail being provided with means for embracing said shoulder, and said tie having a notch in its upper surface positioned and dimensioned to accommodate the lower portion of the shoulder, whereby the rail is secured against creeping.

head for engaging the rail flange to correctly position the rail on the tie, and said tie having a notch in its upper surface positioned and dimensioned to accommodate the lower portion of said shoulder.

11. In combination with a railway tie and a rail lodged thereon, said tie having a vertical mortise formed with a pair of opposing walls approximately parallel; a rail fastening comprising a spike member having a head for engaging the rail flange, and a body portion widening downwardly from said head, and a wedge key of opposite taper adapted for insertion in the tie against the spike member, one face of said spike body being plain and adapted for frictional engagement with one of said opposing walls of the mortise, said spike member having a shoulder formed on the under side of its head, the rail being provided with means for embracing said shoulder, and said tie having a notch in its upper surface positioned and dimensioned to accommodate the lower portion of the shoulder, whereby the rail is secured against creeping.

In testimony whereof, I have hereunto set my hand at Chicago, Illinois, this 23d day of June, 1913.

ANDREW STARK.
